CLOTHES WRINGER AND RINSER

Francis Alward, Boston, Mass.

Application January 14, 1939, Serial No. 250,919

5 Claims. (CL. 68—21)

This invention relates to clothes wringers and has for an object to provide an improved construction of wringer which may act in the automatic capacity of a wringer and rinser.

5 Another object of the invention is to provide a device wherein clothes may be wrung and, if desired, rinsed later by pressing the clothes against a foraminous discharge tube.

A further object of the invention is to provide 10 a combined wringer and rinser for clothes wherein the clothes are wrung by pressure, the device being so constructed that the pressure may be relieved quickly and access may be easily had to the clothes.

15 In the accompanying drawing—

Fig. 1 is a top plan view of a combined clothes wringer and rinser disclosing an embodiment of the invention, a small portion being broken away for disclosing certain detail structures;

20 Fig. 2 is a vertical sectional view through Fig. 1 approximately on the line 2—2;

Fig. 3 is a perspective view of the cap shown in Fig. 2;

25 Fig. 4 is an enlarged fragmentary sectional view of the upper part of the wringer and rinser disclosing how the bag is clamped in place and also certain other detail features;

Fig. 5 is an enlarged fragmentary sectional view 30 through the air relief valve shown in Fig. 2;

Fig. 6 is a sectional view through Fig. 5 approximately on the line 6—6.

After clothes have been washed it is necessary to wring the same before they can be rinsed and also it is necessary to wring the clothes after rinsing before the clothes can be hung up for drying.

35 In large laundries various mechanisms have been provided for accomplishing these results, including a wringing machine having pressing rollers. Wringers using pressing rollers are now 40 in common use in homes but quite often they break buttons and are objectionable for various other reasons.

In the present invention means have been provided for wringing clothes without danger of tearing the clothes or breaking buttons carried thereby. Also the device embodying the invention is adapted to wring and rinse the clothes a second time or oftener if desired, so that clothes placed in a device embodying the invention are treated 50 by a wringing operation and a rinsing operation as often as desired and when removed are completely rinsed and wrung reasonably dry.

55 Referring to the accompanying drawing by numerals, 1 indicates a casing which is preferably made of metal and strong enough to stand

some considerable pressure. A rigid or solid metallic head 2 is welded or otherwise rigidly secured to the upper end of casing 1, while at the bottom the casing 1 is provided with an aperture through which the tubular extension 3 of a 5 foraminous pipe 4 extends. A discharge member 5 extends from the tubular extension 3 and is provided with branch pipes 6 and 7, pipe 6 having a valve 8 to control the inflow of clean rinsing water, while pipe 7 is provided with a valve 9 10 for controlling the discharge water. It will be understood that the valve 8 is closed when valve 9 is open and that valve 9 is closed when valve 8 is open.

15 During the wringing operation water will pass downwardly, as hereinafter fully described, into and through the tubular extension 3 and out through the pipe 7. This removes a large proportion of the soapy water from the clothes. Valve 9 is then closed and valve 8 opened so as to admit water under the usual water main pressure in dwellings or wherever the wringer is located. It will be understood that when valve 8 is open, valve 16 is closed and air exhaust valve 43 is open. The rinsing water is clean fresh water which is 25 forced upwardly through the foraminous tube 4 into the clothes. If there is any soap left in the clothes, the fresh water, which is preferably hot, removes the soap and then on a second wringing operation the soapy rinsing water will be 30 discharged as just described and a second and a third rinsing operation may be carried out if it is thought necessary. After the last operation has been completed the clothes are removed and another batch provided if desired.

35 From Fig. 2 it will be observed that a flexible bag 10 is clamped at the bottom between washers 11 and 12, by reason of the fact that the shoulder 13 of pipe 4 presses against washer 11 under the action of a nut 14 which is threaded on the tubular extension 3. All these devices are firmly clamped together and to the casing 1 and remain in this condition as long as the device is to be used.

The pipe 15 discharges into the casing 1 exteriorly of the bag 10 near the bottom thereof, as 45 shown in Fig. 1. The air or liquid passing through pipe 15 is controlled by a hand-operated valve 16. If air is available this is a desirable element for forcing into the container 1 exterior of the bag 10, for producing a squeezing operation. If 50 air is not available, water under hydrant pressure may be used as this water cannot enter to the interior of the bag 10. Bag 10 may be made from pure rubber, canvas and rubber, or other suitable flexible waterproof and airproof material. It will 55

be observed that the enlarged portion 17 at the bottom of pipe 4 is round and that the bottom of the container 1 is round so that there will be no sharp corners over which the bag must be forced during the wringing or rinsing operation.

Pipe 4 extends approximately two-thirds the way up from the bottom of the container and is open at the top so that the foraminous cone 18 may project into the pipe 4. It will be observed 10 that cone 18 is provided with a reduced tapering portion 19 so that it may be readily inserted into the top of pipe 4. It will also be observed that there is a straight section 20 on cone 18, whereby the cone will support and prevent the upper end 15 of pipe 4 from being forced sidewise. Cone 18 is the tapering bottom part of a cap 21 which is shown more in detail in Figs. 3 and 4. This cap is provided with a tubular body 22 and a radiating flange 23 having ears 24 and 25. The ears 20 24 and 25 are preferably somewhat thickened. As these ears and associated parts are identical a description of one will apply to both.

As illustrated in Figs. 2 and 4, there is provided a pair of links 26 for each ear 25, and these links 25 when in operative position straddle the ear 25. One end of these links is connected to a lever 27 having a cam projection 28' and the other end pivotally connected at 29 to a rod 30 slidably mounted in an ear 31 extending from the head 2. 30 A spring 33 surrounds the lower part of rod 30 and presses against the ear 31 and against the enlarged end 34 so as to give the rod and links 26 a continuous tendency to move downwardly. When the parts are in the position shown in 35 Fig. 4, links 26 are sufficiently loose to be slid off ear 25. When the cap 21 is to be clamped in position, the lever 27 is swung over to the position shown in Figs. 1 and 2, whereupon cam end 28 will be swung downwardly and press downwardly on the lug 25 to bring the spring 33 under tension.

As shown particularly in Fig. 4, there is provided an automatic relief valve 35 which consists of a spring 35', a ball 35'' and means for causing the spring to function, whereby the ball 45 will normally close the passageway 36 which extends downwardly and opens into the interior of the casing 1. The bag 10, as shown in Fig. 4, is provided with an L-shaped annular part 37 50 clamped between members 38 and 39, which may be thin flexible metal members, fiber members, or members of other suitable material. Preferably an annular washer 40 is arranged against the radiating flange portion 41 so that when the various screws 42 are tightened the parts will be 55 firmly clamped to the head 2, whereby none of the air or water forced between the bag 10 and casing 1 can escape. If the pressure of air or water between the bag 10 and casing 1 should be 60 too great, the valves 35 will automatically open and allow a discharge. Two of these valves are shown in the accompanying drawing, but if desired a greater number could be used without departing from the spirit of the invention. These 65 valves are set to operate automatically, while there is provided a manually actuated valve 43 for manually exhausting the air from a point exterior of the bag 10. Valve 43 is shown in detail in Figs. 5 and 6, from which it will be observed 70 that it includes a lever 44 connected to a sleeve 45 having an aperture 46. Sleeve 45 surrounds the hollow projection 47 which opens to the interior of the casing 1. A washer 48 prevents sleeve 45 from moving off the member 47, which latter member is provided with an outlet port 49.

When the ports or openings 46 and 49 are in alignment, air may freely escape from the interior of the casing 1, but when these ports are out of alignment no air can escape at this point but air may escape through the valves 35 if the pressure is too great. It will be observed that by swinging both of the levers 27 to the position shown in Fig. 4 and then swinging the links 26 outwardly, cap 21 may be quickly removed and at a later time reapplied and then clamped in place, as shown in Figs. 1 and 2.

When cap 21 is removed wet soapy clothes are placed in the bag 10 until a desired amount of clothes is in the device. Preferably half or two-thirds of the bag is filled and then air is turned on by opening valve 16. This air will quickly pass around the exterior surface of the bag and as the upper part presents the least resistance said upper part will swing inwardly, as shown in dot-and-dash lines in Fig. 2. As pressure continues the bag will begin to squeeze the clothes and the soapy water will flow therefrom into the foraminous tube 4 or upwardly into the foraminous cone 18. Liquid passing into the cone or into the pipe just mentioned will quickly pass downwardly under the action of gravity and outwardly through pipe 7. After the desired squeezing or wringing action is had, valve 16 is turned off and valve 43 rotated to exhaust the air from the container. As the air is exhausted the valve 9 is closed and valve 8 opened so that clean rinsing water may be inserted in the reverse direction to the outward movement of the soapy water. This rinsing water is preferably hot and the bag may be filled completely or partly as desired. After the rinsing operation is completed valve 8 is turned off and valve 9 opened. Air valve 16 is then opened and the rinsing water is forced out in the same way as the soapy water. This operation of inserting and removing rinsing water may be done as often as desired and after the clothes have been properly rinsed the cap 21 is removed and the clothes removed. If desired, a new batch of clothes may be immediately inserted and the operation of wringing and rinsing performed a 40 second time.

It will be observed that the wringing operation does not twist or mutilate the clothes in any way, but merely presses the same together, at first gently and then firmly, against the pipe 4. In this way all the water is really squeezed out of the clothes and drains out the pipe 7.

In Figs. 2 and 4 it will be observed that the curve of the foraminous tube and funnel approximates the curve of the inside of the tank. By reason of this formation there will be no stretching strain on the bag as it will naturally conform to either of these curves. It will also be noted that though the rinsing water may be forced upwardly through the foraminous tube 4, 55 it may also be directed into the top of the funnel 18 without the removal of the clothes but water may be poured in from a container or be directed into the funnel by a rubber hose or otherwise, as many times as desired. In devices 60 using air or hydraulic pressure to extract water from the clothes the water leaves the clothes only to the extent that the pressure is applied. Where this method is used the pressing diaphragm because of its very construction forms a partial 70 vacuum on one side of the pile of clothes for pressing the same. In the present invention the construction is such as to definitely eliminate any vacuum formed by the use of the center tube 4 and cone 18, which really, in a certain sense, 75

permit the clothes to "breathe" and the water to run out agitated by pressure without any vacuum restriction.

In connection with the automatic safety valve 35, it will be understood that the spring holding this valve in closed position is of a strength equaling the maximum air pressure desired for the wringing operation. As indicated in Fig. 4, serrations 25' are provided which permit free passage of air out of the valve when the air is exhausting in this way and also so as to insure a constant valve pressure not affected by the tension of links 33. It will therefore be seen that the ear 25 actually rests on a portion of neck 2, but by reason of the serrations 25' air is permitted to freely flow when excess pressure in the neck opens the safety valve. Also it will readily be understood that the air vent valve 43, shown particularly in Figs. 5 and 6, is an easily operated valve and, therefore, is desirable, but it will be evident that an ordinary pet cock or other form of valve could be used at this point without departing from the spirit of the invention.

Usually during washing of the clothes, one article of clothing is washed at a time, especially in homes, and when an article of clothing has been washed and is still wet and soapy it is dropped into the bag 10. A second article is then washed and dropped into the bag, and so on until the entire wash has been completed. The rinsing and squeezing operation then takes place and the clothes are ready to be removed and hung up for drying.

I claim:

1. A wringer and rinser of the character described including a container having an opening in the bottom and an opening in the top, a foraminous pipe extending centrally and longitudinally of the container near the top and through the opening in the bottom, a foraminous cone fitting into the open top and telescoping in respect to said pipe, a water and air-proof bag arranged in said container exteriorly of said pipe and foraminous cone, means for directing fluid matter interiorly of the container and exteriorly of the bag to cause the bag to move toward said foraminous pipe for squeezing anything contained in the bag, whereby water therein will pass from the interior of said foraminous pipe and out the lower end thereof, means for directing a rinsing water in a reverse direction through said foraminous pipe into said bag, and a manu-

ally actuated exhaust valve for exhausting the air in said container exteriorly of said bag.

2. A wringer of the character described including a container having an opening at the bottom and an opening at the top, a foraminous tube 5 arranged longitudinally and centrally of said container with the lower end extending through the opening in the bottom, a cap fitting in the opening at the top of said container, said cap being provided with a foraminous cone telescoping with respect to said pipe, an air-tight bag arranged in said container exteriorly of said tube and cone, means for clamping said container, said bag and said tube together at the outlet end of said tube, means for directing air 15 into the container exteriorly of said bag, and means for exhausting air from said container.

3. A clothes wringer and rinser including a casing, a foraminous pipe arranged in said casing, an air-proof bag surrounding said pipe, 20 means for causing air to act on the exterior surface of said bag for squeezing any clothes therein against said pipe, means for directing water from said pipe to a discharge point, and means for directing rinsing water in a reverse direction from 25 said pipe into said bag.

4. A pneumatic wringer and rinser for clothes including a container having a foraminous passageway from the top to the bottom, an air-proof bag connected to the container at the central part of the bottom and to the top near the outer part thereof, said bag surrounding said passageway, means for directing air into the container exteriorly of said bag, means for directing water from said passageway to a point exterior of the container, means for directing rinsing water in a reverse direction through said passageway into said bag, and means for exhausting the air from the interior of the container. 30

5. In a wringer of the character described, a 40 container having an opening at the top, a foraminous passage way extending through said container from the top to the bottom, said passageway including a removable cap having an annular flange provided with a plurality of ears, 45 means coating with said ears for clamping said cap in place, an air-proof bag arranged in said container surrounding said passageway, means for directing air into the container exteriorly of said bag, and means for exhausting said air. 50

FRANCIS ALWARD.
